(57) **CLAIM**

The ornamental design for a lead for a pet harness, as shown and described.

DESCRIPTION

FIG. 1 is a front perspective view of a lead for a pet harness, showing my new design.

FIG. 2 is a front elevation view thereof;

FIG. 3 is a rear elevation view thereof;

FIG. 4 is a right-side elevation view thereof;

FIG. 5 is a left side elevation view thereof;

FIG. 6 is a top plan view thereof;

FIG. 7 is a bottom plan view thereof; and,

FIG. 8 is a perspective view thereof with one end attached to the collar of the pet and the other end attached to the pet harness.

In FIG. 8, the broken lines depict environmental subject matter and form no part of the claimed design.

1 Claim, 3 Drawing Sheets
